UNITED STATES PATENT OFFICE.

THOMAS G. HAWKES, OF CORNING, NEW YORK.

DESIGN FOR THE ORNAMENTATION OF GLASSWARE.

SPECIFICATION forming part of Design No. 20,257, dated November 4, 1890.

Application filed October 10, 1890. Serial No. 367,728. Term of patent 14 years.

To all whom it may concern:

Be it known that I, THOMAS G. HAWKES, a citizen of the United States, residing at Corning, in the county of Steuben and State of New York, have invented and produced a new and original Design for the Ornamentation of Glass and other Ware, of which the following is a specification, reference being had to the accompanying drawings, forming part thereof, in which—

Figure I is a bottom view of a glass dish showing my design. Fig. II is an axial section on the line II II, Fig. I.

The leading features of my design consist of the large central figure having radial leaves and the flowers between the outer portions of the leaves, thus forming what I call the "chrysanthemum" design.

1 are the leaves extending radially from a common center, having cross-cut blades 2 and 20 ovate stalks 3. Between the leaves are flowers 4, having central rosettes 5. Small fans 6 appear where the leaves separate. Surmounting or located at the outer ends of the leaves between the flowers are large paired fans 7. 25

Having thus described my invention, the following is what I claim as new therein and desire to secure by Design Letters Patent:

The design for the ornamentation of glass and other ware, substantially as herein shown 30 and described.

THOMAS G. HAWKES.
